UNITED STATES PATENT OFFICE.

WILLIAM A. DYER, OF VESTAL, NEW YORK.

INCUBATOR.

1,122,705.

Specification of Letters Patent. Patented Dec. 29, 1914.

Application filed June 3, 1912. Serial No. 701,273.

To all whom it may concern:

Be it known that I, WILLIAM A. DYER, a citizen of the United States, residing at Vestal, in the county of Broome and State of New York, have invented certain new and useful Improvements in Incubators, of which the following is a specification, reference being had to the accompanying drawings.

10 This invention relates to new and useful improvements in fireless incubators and more particularly to a hot water incubator, the object of the invention being to provide an incubator of this character wherein sufficient heat is produced by radiation from a sufficient volume of water retained at a proper temperature by the introduction of hot water at proper intervals.

Another object of the invention is to provide a hot water incubator wherein a perfect system of ventilation is assured and also the proper amount of moisture produced.

25 A further object of the invention is the provision of an incubator of this character which will possess advantages in points of efficiency, and durability, is inexpensive to manufacture and at the same time is simple in construction and operation.

30 With the above and other objects in view, the invention consists in the novel features of construction and the combination and arrangement of parts hereinafter more fully described, pointed out in the claim, and 25 shown in the accompanying drawings, in which,

Figure 1 is a perspective view of an incubator constructed in accordance with my invention. Fig. 2 is a top plan view, the 40 cover being removed to show the interior thereof. Fig. 3 is a longitudinal sectional view taken on the line 3-3 of Fig. 6, the left hand end thereof being taken on lines 3-3 of Figs. 4 and 6. Fig. 4 is a sectional view on the line 4-4 of Fig. 3. Fig. 5 is a sectional view on the line 5-5 of Fig. 3. Fig. 6 is a fragmentary horizontal section taken on the line 6-6 of Fig. 3.

Referring more particularly to the drawings, 1 indicates the body of the incubator suitably supported by means of the standards 2. Arranged within the body adjacent the bottom thereof are the egg trays 3 which are suitably supported by means of the cleats 4 secured to the side wall and the central guide member 5. Arranged within

the casing and disposed directly above the egg trays is a suitable tank 6 having outwardly extending flanges 7 formed at its ends and side edges which are adapted to rest upon the cleats 8 to support the tank. The walls of the body are provided with a dead air space 9 and an exhaust space 10. The tank 6 is so arranged in the body as to leave an air space 11 between the top of the tank and the top of the body of the incubator. The tank 6 is provided with an inlet pipe 12 which passes down through the space over the tank and extends into the tank through the top thereof. A cap 13 is threaded over the outer end of the inlet pipe to close the same when not in use.

Opening up through the bottom of the body of the incubator at each end thereof are the fresh air inlet openings 14 through which the fresh air passes, and thence upwardly through openings 14' into the air spaces 9 to a point opposite the space over the tank. The air then passes in one end of the pipes 15, said pipes extending in opposite directions lengthwise of the tank and returning to and through the same wall, then down through the dead air space to a point beneath the tank. The pipes then extend through the wall of the egg chamber 80 to conduct the heated air in the egg chamber, the warm air being diffused down through and around the eggs so that oxygen is taken in by the eggs, the same being very essential to the proper development of 90 embryo. After the warm air has circulated through the egg chambers, the same passes down through the exhaust openings 15' and is then conducted through the air passages 16 and openings 16' to the exhaust 95 passages 16' where the same is passed off up through the openings 17' and 17, said latter openings being closed by means of the sliding shutter members 18 arranged upon the body. The inlet openings 14 are closed by 100 means of the shutters 18.

A drawoff pipe 19 extends transversely through the side walls of the body and into the tank near the bottom thereof to draw off the water when the same becomes cooled. Arranged at the end of the tank opposite the pipe 19 is an emergency outlet pipe 20 to be used in case an inexperienced operator has too much heat caused by putting in too much heated water.

110 It will be seen that the exhaust openings 15' in the bottom of the egg chamber are

substantially centrally located and as the air passes down through the same, it is conducted through the passages 16, which extend to the four corners of the body, the air is then conducted up through the exhaust passages 16' and out through the openings 17. The section line 3—3 in Fig. 6 of the drawings indicates the line upon which the uppermost bottom member of the 5 double bottom is sectioned in Fig. 3 of the drawings. It will be readily seen that the means for supplying heated fresh air to the egg chamber is extremely simple. As the 10 fresh air passes in through the openings 14, it is conducted up through the space 16 and then enters one end of the pipes 15 which extend lengthwise of the tank on the top thereof and return to and through the same 15 wall and then down through the air space 6 20 to a point beneath the tank. These pipes 15 are heated by means of steam and hot air escaping from the tank through the pipes 21 which extend upwardly and out through the top of the tank from a point near the 25 bottom thereof.

Sufficient moisture is supplied to the egg 30 chambers by means of the short pipes 22 having one end opening into the space 11 above the tank and the other end of said 35 pipes extending outwardly into the air space 6, thence downwardly and into the egg chamber at a point above the trays 3. An air vent 23 is formed in the top of the tank and is closed, when not in use, by means of 40 the plug which extends through coinciding 45 openings in the top of the body.

From the above description taken in connection with the drawings, the use, advantages, and operation of my improved incubator will be readily understood and it will 40 be apparent that I have provided a fireless incubator wherein a perfect system of ventilation is assured and the proper amount of moisture is obtained at all times.

45 While I have shown and described the pre-

ferred form of my invention, it will be obvious that various changes in the details of construction and in the proportions may be resorted to for successfully carrying my invention into practice without sacrificing any 50 of the novel features or departing from the scope thereof.

What I claim is:—

In an incubator, a casing provided in its 55 end walls with inner and outer air chambers and additional corner chambers, a plurality of division walls arranged in the inner air chambers dividing the same into a plurality of isolated compartments, a cover for the casing closing the upper ends of said chambers, egg trays arranged in said casing, a tank suspended in the casing above the egg trays said tank having openings in its top wall, air receiving pipes arranged over said tank, each of said pipes having one of its 60 ends in communication with the central compartment of the inner air chamber in the respective end walls of the casing and the other end of said pipes opening into the space beneath said tank and above the egg 65 trays, the bottom wall of the casing being provided with air inlet openings in communication with said central compartments, an additional pipe extending through one of the compartments in one of the end walls of 70 the casing and communicating at its ends with the space above the tank and the space below said tank respectively, said bottom wall of the casing and the cover being further provided with passages in communication with the corner chambers of the 75 casing and with the space below the egg trays whereby the vitiated air is exhausted.

In testimony whereof I hereunto affix my 80 signature in the presence of two witnesses. 85

WILLIAM A. DYER.
